UNITED STATES PATENT OFFICE

BERTRAM NORTON, OF CLAVERLEY, ENGLAND, ASSIGNOR TO NORTONS (TIVIDALE) LIMITED, OF TIPTON, ENGLAND, A BRITISH COMPANY

COAL WASHER BOX

Application filed March 29, 1928, Serial No. 265,734, and in Great Britain April 26, 1927.

This invention relates to washer boxes for coal and the like of the type in which the material to be washed is caused to travel over perforated plating through which water is caused to rise and fall in pulsations under the action of air under pressure, or by any equivalent means. In washer boxes of this type the shale is separated from the coal owing to difference in density, and during normal working a bed of shale is allowed to form on the perforated plating.

Generally in such washer boxes the shale is discharged from the washing bed through an aperture controlled by a gate moving in guides, with the result that the weight of the coal and shale forces the gate against the guides so that considerable frictional resistance has to be overcome before it can be moved. It is the principal object of the present invention to provide an improved form of gate which shall be very easily moved and shall be particularly suitable for automatic control. It is a further object of the present invention to ensure that any risk of incomplete closing of the gate shall be eliminated so that positive action can be ensured when the box is worked automatically. Another object of the present invention is to control the operation of the improved gate by means of a float device in accordance with the depth of the shale layer, so that when the layer builds up above a predetermined height the gate shall be opened and the shale allowed to flow out, but on the layer sinking below a predetermined height the gate will close again.

Yet a further object of the invention is to provide an improved form of float, and to mount it so that it will always remain truly vertical, and further to connect the float to control the gate through a compressed air relay mechanism. Such a relay mechanism is particularly suitable for use in coal washer boxes of this type, since the pulsations of the water are generally produced by means of compressed air which is consequently easily available. Owing to the pulsations of the water, the float will always rise and fall slightly even though the depth of the shale remains constant. This would produce cor-

responding variations in the position of the control valve of the compressed air relay mechanism which would be most undesirable, and accordingly another object of the invention is to allow the float to move with the pulsations of the water without actuating the relay mechanism. 55

With these and other objects in view, according to the present invention, the gate controlling the discharge of the shale is mounted outside the limits of the washing bed, and conveniently may be pivotally mounted so as to swing outside the forward edge of a shelf projecting from beneath the aperture in the walls surrounding the washing bed through which the shale flows out. 60 This gate may then be arranged to lie beneath the shelf to allow the shale free discharge, but to swing upwards and intersect the out-flowing stream of shale when it is desired to stop the shale discharge. It is found that with such a gate the discharge of the shale is stopped entirely when the leading edge of the gate reaches the level of the top of the aperture irrespective of the height of the top surface of the working bed above the aperture. 65 Such a gate is very easily moved since it is not forced by the weight of the shale and coal against any guides, and so it is particularly suitable for automatic control through a relay mechanism by means of a float. Conveniently a lost motion device is inserted between the float and the relay mechanism so as to allow the float to respond to the pulsations of the water without actuating the relay mechanism. 70 In order to maintain this float truly vertical it is preferably carried by means of a parallel motion mechanism. By this means it is effectually prevented from jamming or sticking. The improved float 75 may be made as a hollow body into which weighting material can be filled, so that it will sink through the coal layer but rest upon the shale layer, and it may conveniently be made of elongated cross-section or may be 80 stream-lined so that the washing water and material will pass it easily. 85

The invention will be more clearly understood from the following description of one form of box, constructed in accordance there- 100

with, which is illustrated by way of example in the accompanying drawings, in which

Figure 1 is an elevation partly in section;

Figure 2 is an end elevation partly broken

5 away;

Figure 3 is a plan of the coal inlet end of the washer box;

Figure 4 is a view showing a modified form of shale outlet gate; and

10 Figure 5 is a fragmentary detail, partly in section, showing diagrammatically the means for admitting compressed air to cause pulsations of water in the washer box.

15 In the drawings only so much of the washer box is shown as is necessary to understand the present invention. The box 1, to which coal and shale to be separated is fed, is provided with a perforated plating 2 through which the water is caused to rise and fall in pulsations under the action of air under pressure in the usual way by means of a mechanism to be hereinafter described, and the action of the pulsating water causes the separation of the coal and shale into two layers.

20 25 It may be assumed that the specific gravity of shale is about 1.60, while that of coal is about 1.35, so that on each lift or upward pulse of the water the shale bed is loosened and partially lifted, and any coal still en-trapped in the shale tends to be washed out.

The coal which is delivered to the box down a chute 32 over the top edge 3 of the end wall of the box 1, passes away over a similar wall at the other end, and is removed by suitable

30 35 elevating apparatus, while the shale passes out through an aperture 4 formed in the end wall. The width of the aperture 4 may be varied by means of an adjustable plate 5. A shelf 6 projects from the lower edge of the

40 45 aperture 4 and away from the box and is ar-ranged on a slight slope, and provided with perforations so that the water may pass through the shelf, and thus assist the move-ment of the outflowing shale. A gate having a closure surface 7 in the form of a sector of a cylinder carried on arms 8 pivoted about a longitudinal axis 9 preferably disposed out-side the box and spaced from the outer edge

50 55 of the washing bed and is free to swing from the position shown in full lines in Figure 1 to the position shown in dotted lines in which it lies beneath the shelf 6. Due to the shape of the gate, it maintains substantial contact with the outer edge of the shelf in all posi-tions of such movement. This shelf 6 is pro-vided at either end with upstanding walls 10

60 65 so that a chute or spout, open at the top, is formed, the forward edge of which is con-trolled by the gate 7. When the gate 7 is in the position shown in full lines in Figure 1 the flow of shale from the box is stopped en-tirely, but when it is swung into the position shown in dotted lines the shale flows freely out through the aperture 4 and falls down-

wards from the edge of the shelf 6. The gate, therefore, does not abut against or close any aperture, but presents a barrier or weir to the flow of shale, the height of which barrier is variable relatively to the shelf 6 and to the upper surface of the shale.

70 75 The gate 7 is bodily rocked in its arcuate path about the axis 9 by means of a handle 11. This handle may be moved by hand, but as shown it is arranged to be operated in accordance with the depth of the shale layer in the box 1 by means of an automatic float device.

75 80 This comprises a hollow float 12 which is weighted by adding weighting ma-terial until it will just sink through the coal layer but will rest upon the shale bed. This float 12 is carried by a parallel motion link-age, one side 13 of which is arranged parallel with the vertical axis of the float. The two

85 90 side links 14 and 15 are horizontal in the nor-mal position of the float 12, and each oscillate about a horizontal axis as the float rises and falls. The fourth side of this linkage con-sists of fixed frame members 16 and 17 formed

95 100 as a bracket extending respectively upwards and downwards from a cross bar 18 extend-ing transversely across the box 1. A rocking

105 110 spindle 19 is rigidly connected to the top links 14 of the parallel motion linkage so that as these links 14 oscillate the spindle 19 oscillates also. This spindle 19 carries rigid-ly fixed to it a depending arm 20, the lower

115 120 end of which moves between two stops 27 formed integrally with the lower end of an arm 36. This arm 36 is rigidly fixed on the end of a spindle 37 pivotally mounted in bear-ings 38 and having a depending arm 39; the free end of which is pivotally connected to a rod 21.

125 130 This rod 21, which is thus moved when the float 12 rises or falls more than a small amount, controls the operation of a relay mechanism which in its turn controls the operation of the gate 7. When the float

135 140 merely rises and falls with the pulsations of the water, however, the arm 20 will move be-tween the stops 27 but will not rock the

145 150 spindle 37.

155 160 The relay mechanism comprises a cylinder or casing 22 in which moves a sliding piston

165 170 valve 23 connected to the rod 21. Com-pressed air is admitted to the casing 22 through a pipe 24. The sliding piston valve 23 is made hollow, and is formed with a central part 25 of reduced diameter so that

175 180 the air through the pipe 24 arrives at the an-nular space around this reduced part 25. The casing 22 is formed with a port 26, which in the normal position of the float 12 is cov-ered by one end of the piston valve 23.

185 190 When the float rises the piston valve 23 is moved to the left in the drawings, so that the port 26 is uncovered, and air under pressure is ad-mitted to the face of a large piston 28 which

195 195 slides in a cylinder 29. A rod 30 of this pis-ton 28 carries a wheel 31 which bears against

200 205 the outer edge of the shelf 6. The piston 28 is

210 215 held in its normal position by a spring 32 which is attached to the piston 28 and to the

220 225 outer wall of the cylinder 29. The piston 28

230 235 is held in its normal position by a spring 32 which is attached to the piston 28 and to the

the handle 11 so that as the piston 28 moves to the left the handle 11 is forced over to the left also, thus swinging the gate 7 downwards beneath the shelf 6. The shale then flows freely out through the aperture 4 until the float 12 sinks, pulling the rod 21 and piston valve 23 to the right, and thus closing the port 26. When the piston valve 23 moves further to the right it will uncover the port 26 so that the air passes out from the cylinder 29 through this port, through the hollow centre of the piston valve 23 and so out to the atmosphere through the end of the casing 22. The gate 7 will then automatically swing upwards because the handle 11 is connected by means of a rope 33 and pulleys 34 to a restoring weight.

It will be realized that the adjustment of the float 12 is comparatively delicate, and it is always desirable, therefore, to operate the gate 7 through a relay mechanism such as that shown. It is further found desirable to make the float 12 of elongated cross-section as shown, so that the material and washing water flowing through the box 1 will pass it easily, and further for the sake of greater accuracy the actual linkage carrying the float is balanced by a weight 35 rigidly connected to the transverse rod 19.

Figure 4 shows a part of a washer box having a modified form of shale outlet gate. In this case the gate 7 still has its closure surface formed as a sector of a cylinder, but the axis 9 about which the gate is pivoted is spaced well away from the outlet aperture 4 so that the surface of the gate 7 lies between the axis 9 and the aperture 4. In this case the gate is shown in its closed position in full lines, and swings, so as nearly to touch the forward edge of the perforated shelf 6, into the position shown in dotted lines in which the outflowing shale flows over the closure surface of the gate and then drops downwards.

By reference to Figure 5, wherein is shown diagrammatically a means for admitting compressed air to cause pulsations of water in the washer box, air under pressure from a suitable source passes from line 40 through port 43 of a valve element 42 arranged in a valve bonnet 41, and thence to a compartment formed by wall 46 extending below the normal liquid level in box 1, thereby causing a surge or pulsation in a known manner. Upon rotation of the valve element 42 as by a suitably driven cable 48 and pulley 47, air in the aforesaid compartment may be vented upon ports 44, 45 coming in registry to cause a return pulsation or surge. Equivalent means for causing such pulsations or surges may of course be substituted.

Although one construction of washer box according to the invention has been described in detail, the invention is not, of course, limited to this.

The shale outlet gates are generally provided at both ends of the washer box so that it will generally be desirable to provide separate floats for the shale outlet gates at the inflow and outflow ends because the rates of discharge will be different.

Having thus described my invention what I claim as new, and desire to secure by Letters Patent, is:—

1. A coal washer box having an end discharge aperture, a shelf projecting from the lower edge of the aperture and away from the box, a gate supported on and swingable about an axis outside the box and spaced from the outer edge of the shelf, mechanism responsive to variations in the shale level in the box to swing the gate to a position below the upper surface level of the shelf and to a position above said shelf, the gate being shaped to maintain substantial contact with the outer edge of the shelf in all positions.

2. A coal washer box having an end discharge aperture, a shelf projecting from the lower edge of the aperture and away from the box, a gate supported on and swingable about an axis outside the box and spaced from the outer edge of the shelf, mechanism responsive to variations in the shale level in the box to swing the gate to a position below the upper surface level of the shelf and to a position above said shelf, the gate being in the form of a sector of a cylinder to maintain substantial contact with the outer edge of the shelf during such swinging movement.

3. A coal washer box having an end discharge aperture, a shelf projecting from the lower edge of the aperture and away from the box, a gate supported on and swingable about an axis outside the box and spaced from the outer edge of the shelf, mechanism responsive to variations in the shale level in the box to swing the gate from a normal position nearly completely below said shelf and to a position above said shelf, the gate being in the form of a sector of a cylinder and maintaining substantial contact with the outer edge of the shelf during such swinging movement.

4. In a coal washer box comprising a receptacle in which the material under treatment is maintained as a washing bed, said receptacle being formed with an aperture for the discharge of shale from said washing bed, the combination of a shelf projecting from beneath said aperture and beyond the end of the receptacle, a gate extending in an upwardly inclined position, pivoted remotely from the shelf and bodily movable along an arc located outside the forward edge of the shelf and which extends above and below the shelf, and means responsive to variations in depth of the shale layer to operate said gate.

5. In a washer box for coal in which the material under treatment is maintained as

- a washing bed, in combination, a receptacle for said washing bed, one of the walls of said receptacle being formed with an outlet aperture for the shale, a shelf projecting from beneath said aperture, a perforated bottom to said receptacle, means for admitting compressed air to cause pulsations of water through said perforated bottom, a movable gate normally disposed below said shelf but capable of moving upwards through the out-flowing shale to co-operate with the forward edge of said shelf, a float so weighted as to sink through the coal layer but to float upon the shale layer, a compressed air relay mechanism formed with air passages and operatively connected to move said gate and a valve member forming part of said relay mechanism and actuated upon the rise and fall of said float to control said air passage.
6. In a washer box for coal in which the material under treatment is maintained as a washing bed, in combination, a receptacle for said washing bed, one of the walls of said receptacle being formed with an outlet aperture for the shale, a shelf projecting from beneath said aperture, a perforated bottom to said receptacle, means for admitting compressed air to cause pulsations of water through said perforated bottom, a movable gate normally disposed below said shelf but capable of moving upwards through the out-flowing shale to co-operate with the forward edge of said shelf, a float so weighted as to sink through the coal layer but to float upon the shale layer, a compressed air relay mechanism comprising a casing formed with passages, a piston valve sliding in said casing and co-operating with said passages, said valve being operatively connected with said float so as to be actuated in accordance with the rise and fall thereof, a cylinder communicating with said casing by one of said passages, and a piston sliding in said cylinder and operatively connected to open said gate.
7. In a coal washer box in which the material under treatment is maintained as a washing bed, a receptacle for said washing bed, a member rigid with said receptacle, a float so weighted as to sink through the coal layer but to float upon the shale layer of said washing bed, and parallel motion link connections between said member and said float, said link connections being so disposed as to maintain said float vertical.
55. In witness whereof I hereunto subscribe my name this 16th day of March A. D., 1928.

BERTRAM NORTON.
